UNITED STATES PATENT OFFICE.

RICHARD M. HOPKINS, OF NEW YORK, N. Y., ASSIGNOR TO AMERICAN DISTRICT TELEGRAPH COMPANY, OF JERSEY CITY, NEW JERSEY, A CORPORATION OF NEW JERSEY.

SIGNALING DEVICE.

1,387,399.

Specification of Letters Patent.

Patented Aug. 9, 1921.

Application filed January 27, 1917. Serial No. 144,953.

To all whom it may concern:

Be it known that I, RICHARD M. HOPKINS, a citizen of the United States of America, and a resident of New York, in the county of 5 New York and State of New York, have invented certain new and useful Improvements in Signaling Devices, of which the following is a specification.

My invention relates to improvements in 10 signaling devices, and particularly means for making prominent a distinctive signal transmitted over a circuit normally occupied with signals of another class. My invention further comprises means whereby, by means 15 of relays of approximately normal type, and controlled one by another in a species of series relation, the operation of a final signal-giving device may be deferred as desired and may be made dependent upon the elapse of 20 such time-interval as desired.

The object of my invention is to defer, by the action of simple and reliable means, the operation of a signal-giving device through such time-interval as desired, and to make 25 the operation of such signal-giving device dependent upon the elapse of such time-interval as desired; also to provide simple means for making prominent a distinctive signal transmitted over a circuit normally 30 occupied with signals of another class.

I will now proceed to describe my invention with reference to the accompanying drawings, which illustrate diagrammatically one arrangement of apparatus embodying my 35 invention. In said drawings:

Fig. 1 is a diagram illustrating the application of my invention to a typical combined watchman's signal and fire alarm system.

Fig. 2 shows a fragmentary diagrammatic elevation of a characteristic break wheel and contact pen mechanism of a combined watchman's signal and fire alarm box.

Fig. 3 shows a longitudinal vertical section of the magnet of a short circuited core relay such as hereinafter referred to.

It is now common to combine watchmen's signal and fire alarm systems, the same transmitters (commonly called signal boxes) and 50 the same circuit being employed for both classes of signals. Commonly, the said signal boxes are arranged to send numerical signals, each such signal distinctive of the particular box from which it is sent; and

commonly the watchman's signal consists of 55 a single round of a box number, whereas the fire signal consists of a plurality of rapidly-succeeding rounds of such signal. The watchman's signal may be further distinguished from the fire signal by 60 having associated with the box number a further signal, such for example as a long dash either preceding or following the box number, or the Morse letter F (dot, dash, dot) preceding or following the box number, 65 or preceding or following one or more rounds of the box number when the fire signal (as distinguished from the watchman's signal) consists of a greater number of rounds of the box number than does the watchman's signal. 70 Both the watchmen's signals and the fire signals are commonly received on an ordinary telegraph register, which imprints, impresses, or perforates the signals received on a paper tape or other record surface. One 75 object of the present invention is to cause the fire signals to operate some distinctive signal-giving device (such as a loud bell, or a lamp) other than, or in addition to, the register or other instrument upon which the 80 watchmen's signals are normally received.

While my invention is particularly applicable to combined watchmen and fire alarm signal systems, wherein signals for one class of service (fire signals, for example) are distinguished from signals for another class of service (watchmen's signals, for example) by a distinguishing signal containing or consisting of a dash longer than those occurring in the box number, yet my invention is obviously adaptable to and useful in connection with various other types of apparatus and systems; and therefore it is to be understood that in illustrating and describing my invention in connection with a combined 85 watchman and fire alarm system, I do not in any way limit my invention to use in connection with such a system.

In Fig. 1, 1 designates a signal box circuit, shown fragmentarily only, and containing 100 a plurality of signal boxes 2, a battery or other source of current supply 3, and a central-station relay 4, which latter may be a relay of the ordinary type, arranged to repeat signals transmitted through circuit 1 105 into a circuit 5 containing a battery or other source of current supply 6 and an ordinary telegraph register 7; by which latter instru-

ment the signals received are recorded. The signal boxes 2 are to be understood to be boxes which, when operated for watchmen's signals, transmit the number of the box one or more times; and which, when operated for fire signals, transmit, in addition to the box number, a distinctive fire signal consisting of, or containing, a dash of greater length than is contained in the box number.

10 As so far described, the instruments and circuits are those of an ordinary combined watchman and fire alarm signal system.

15 8 and 9 designate slow-acting relays, preferably shortcircuited-core relays such as hereinafter described. The magnet of relay 8 is included in circuit 5 of the register 7; and the front contact stop of the relay is also connected to circuit 5, the armature of relay 8 being connected to a conductor 10 leading to the magnet of relay 9, and thence to circuit 5. The magnets of relays 8 and 9 are preferably shunted by resistance 11. The armature and front contact stop of relay 9 control a circuit 13 containing a 20 battery or other source of current supply, 14, and a bell or other distinctive signal device, 15.

25 It is to be understood that relays 8 and 9 are together so slow acting that circuit 13 will not be closed during the dots of the signals of the boxes 2, but that such circuit 13 will be closed upon transmission of a much longer impulse—for example, a dash.

30 It is of course true that different relays 35 of the ordinary type may be adjusted to make contact with signals of one length, but not to make contact with signals of less length; and some types of relays are less sensitive than other types; further, slow 40 acting relays have been produced by weighting the armature, or by attaching a dashpot or other retarding device to the armature, or by connecting a fan train to the armature. But dash-pots, fan trains and other mechanical 45 retarding devices are objectionable, particularly in the case of fire-signal relays, which should have as few mechanical complications as possible; and ordinary slow-acting telegraph relays not provided with 50 dash-pots, or fan trains, or like mechanical retarding devices, are not sufficiently slow-acting, and at the same time sufficiently positive in action, for my purpose; and furthermore do not have, at least to a sufficient extent, the hereinafter described quality of 55 compensating for different speeds of signal boxes.

60 I have found that a relay the core of which is surrounded by a tube of high-conductivity metal, may be slow-acting to a surprising degree, and yet is very positive in action. Such a relay is shown in Fig. 3, where 16 designates the core proper, of highly magnetizable metal (usually 65 soft iron), 17 designates the surround-

ing tube or sheath of high-conductivity metal (usually copper), 18 designates the spool, 19 the windings upon the spool, and 20 the armature. A magnet having a core surrounded by such a high-conductivity 70 sheath is said to have a short-circuited core. When an electric circuit is closed through the windings of a magnet having such a core, the eddy currents generated inductively in the conductive sheath 17 so retard the rise 75 of magnetization in the core, that considerable time elapses before full magnetization to, or approaching, saturation, is reached. Such a relay, properly constructed, may be relied upon to occupy one-quarter second or 80 more in attracting its armature sufficiently to close contact, without an unduly long travel of the armature, and with positive and certain response of the armature, and a firm contact when the front stop is reached. 85 Similarly, the movement of the armature from its front stop to its rear stop is greatly retarded, as compared with the action of an ordinary relay. A number of such relays, connected in series or "cascade", as are relays 8 and 9 of Fig. 1, may be arranged to 90 give any desired delayed action, the number of relays so employed being dependent upon the period of delayed action desired.

Owing to the considerable delay obtained 95 by the combined operation of slow-acting relays 8 and 9, the contacts of relay 9 do not respond to short impulses, such as occur during the transmission of the impulses of the box number but do respond to the dash of 100 the Morse letter F, so operating the signal device 15.

105 It is to be noted that relays 8 and 9 are partially short-circuited by a non-inductive resistance 11.

The purpose of this resistance 11 is to permit the current value to rise quickly to that necessary for operating register 7, also to shunt out a portion of the current passing through relay 8 so as to slow down the action 110 of this relay in attracting its armature. When the contact of relay 8 is completed the combined resistance of the magnet of relay 8, and the non-inductive resistance 11 then places a shunt of a low resistance across the 115 terminals of the magnet of relay 9, which slows down the action of that relay in attracting its armature; thereby relay 9 is prevented from closing its contacts when short 120 impulses pass through its magnet, while when a long impulse, such as that of the dash of the Morse letter F, passes through such magnet of relay 9, the contacts of the relay are closed. In other words, short impulses do not afford a sufficient time for the magnetization of the magnets of relays 8 and 9 to rise to such value that the contacts of relay 9 125 are closed; but a dash, such as that of the Morse letter F, does afford a sufficient time for rise of magnetization in magnet of relay 130

9 to the point where the contacts of that relay will close.

Owing to various circumstances, the retarding effect of the shortcircuited core of 5 the magnets of these relays 8 and 9, is more prominent in the case of movement of the armature away from the core, than in the case of movement of the armature toward the core.

10 In Fig. 2, 21 designates the toothed break wheel, and 22 a contact pen adapted to be raised from contact member 23 by engagement of 22 by the teeth of the break wheel.

This case is a continuation in part of my 15 prior application which eventuated in Patent No. 1,308,772.

What I claim is:

1. In a signaling system, the combination of a circuit including one or more signal 20 transmitters, of a relay controlled by said circuit, a second circuit comprising a register and a plurality of slow-acting relays connected in parallel, the circuit of one of said 25 relays being closed through the front contact of the other relay.

2. In a signaling system, the combination of a circuit including one or more signal transmitters, of a relay controlled by said circuit, a second circuit comprising a register, a relay having resistance shunt across 30 its terminals, and a slow-acting relay in shunt to said first-named relay and having its circuit closed through the front contact of the latter.

3. In a signaling system as set forth in 35 claim 1, a third circuit including a signaling device and controlled by the armature of the said controlled relay.

4. In a signaling system, as set forth in 40 claim 2, a third circuit including a signaling device and controlled by said slow-acting relay.

In testimony whereof I have signed this specification in the presence of two subscribing witnesses.

RICHARD M. HOPKINS.
